APPARATUS FOR RENOVATING MOLDING SAND

Willard J. Bell, Newaygo, Mich.

Application October 26, 1938, Serial No. 236,980

4 Claims. (Cl. 83—11)

This invention relates to an apparatus and a method of renovating molding sand after the same has been used in flasks in casting and from which it is removed. Such sand coming from the flasks has parts thereof burned, others baked and adhering together. There are pieces of metal and sometimes of wood in the sand and from the burning which has occurred ashes and very fine dust occur, which should be removed. After the sand has been once used in flasks in the operation of molding it is necessary from cost considerations to reuse the sand, with the addition of water, bonding material and the like, to properly prepare the sand for its subsequent use in molding.

The present invention is concerned with the first step in the renovation of the used sand and has for its primary object and purpose the breaking up of the chunks and bodies of sand which are packed or otherwise adhere together, the removal of ashes and dust and the removal of metallic and wood parts which have come from the casting, particularly iron fins and the like which are not large enough to be readily removed either manually or in practice magnetically.

With my invention the sand which has been previously used in a casting operation is prepared for mixing with added materials which must be supplied before the sand is again in suitable shape for use, and at the same time increase the efficiency of the mixing machine which is the subject matter of a copending application for patent filed by me on October 26, 1938, and bearing Ser. No. 236,979, and prepare and renovate the sand so that it will mix better, freeing the sand of all metallic fins, pieces of wood and other undesired materials and removing ashes and dust in a very practical and efficient manner.

An understanding of the invention may be had from the following description, taken in connection with the accompanying drawings, in which:

Fig. 1 is a vertical section taken from what may be termed the front to the rear of the machine.

Fig. 2 is a vertical section substantially on the plane of line 2—2 of Fig. 1, and

Fig. 3 is a perspective view of a detail of structure relating to the grate or screen bars which are spaced apart and between which the renovated sand is delivered from the machine.

Like reference characters refer to like parts in the different figures of the drawings.

In the construction of the machine a substantially enclosed housing is provided which for purposes of easy assembly is divided horizontally into two parts or sections. The lower section has spaced apart vertical sides 1 between which at their front and rear edges are front and rear vertical end members 2. Angle bars 3 surround this lower portion of the housing at the lower end thereof and are bolted in place as shown. The underside of the housing is open, the sand being delivered from the machine at such open under side usually to a conveyor belt which is to carry the renovated sand to the mixing machine for the next step in preparing the sand for molding use.

The upper section of the housing has two spaced apart vertical sides 4 immediately above and in the same plane with the sides 1, and a front 5 immediately above and in the same plane with the front member 2 of the lower part of the housing. The upper and lower sections of the housing are connected together by angle bars such as indicated at 6 in Fig. 1, it being evident that the bolt connections permit a ready assembly of the parts. At the upper side and at the rear part of the housing is a top 7 extending over approximately one-half of the upper side of the housing to which a second top or cover plate 8 is hingedly connected by hinges shown at 10. Angle bars 9 are bolted at the upper ends of the sides for connection of the top member 7 and the front 5, and the hinged cover member 8 may have the bolts which connect it to said angle bars removed, permitting lifting for access to the interior of the machine when desirable or necessary.

At the inner side of the housing and particularly at those portions where the sand which is to be operated upon strikes against the housing, it is lined with wear plates 11 to 17 inclusive. The plates 11 and 12 are at the inner sides of the sides 4, the wear plates 13 and 14 are of sector-like shape as best shown in Fig. 1 and cover a portion of the lower parts of the side plates 4 and of the upper parts of the side plates 1 of the housing. The plate 15 is at the inner side of the vertical front 5 and those at 16 and 17 underneath the cover or top members 7 and 8. Such plates are bolted in place and can be readily removed and replaced by removing the bolts when after a period of operation of the machine the wearing away of the plates has made it advisable that they be replaced with new ones.

Near the lower portion of the housing at each

- side thereof two spaced apart curved guide bars 18 and are secured at the inner side of each side of the housing. The curved edges of the wearing plates 13 and 14 come against the upper 5 curved edges of the bars 18 (Fig. 1). Between these pairs of spaced apart bars 18 and 19 screen or grate bars 20, preferably of tool steel, are located, extending across from one side to the other of the housing, and having their ends received and guided between the curved guide bars 18 and 19. Alternate bars 20 at their ends have wedge blocks 21 secured thereto by a pin 22 (Fig. 3), the wedges serving to space the adjacent bars short distances apart and thereby making 10 a grating or screen for sand to pass through. It is of course to be understood that while, as in Fig. 3, alternate bars carry both the wedges 21, it is quite the same thing to have each of the bars at each end carry one of the wedges 21. 15 20 instead of alternate bars carrying two of them. The wedges 21 may be turned about the axis of the pin 22, thus permitting the bars 20 to be turned over or reversed in position, for example when they become worn at their upper edges. 25 In such case a turning over of the bars presents the new lower edges of the bars at the upper side, thus permitting the bars to be used twice as long as would be the case if it was necessary to replace them after the upper edges thereof had 30 become worn.
- The end bars 20 of the curved screen or grating come against an angle bar stop 23 and a heavy breaker plate 24 which hold them against movement or displacement. The stop provided 35 by the member 23 is bolted in place at the inner side of the front member 5 of the housing after the screen bars have been assembled between the curved guides 18 and 19. The breaker plate 24 which is relatively thick and heavy is guided 40 by the spaced guides provided by the angles 25 and 26, the latter extending upwardly and to the rear from the lower curved bar 19 and forwardly from the inner or upper curved guide 18. The guide 25 is longer than the guide 26 and extends 45 to the top of the housing. At its upper portion it serves, together with a third guide angle bar 26a located above the breaker plate 24, to hold a closure plate 27. It is of course to be understood that the guiding bar structure including 50 the angle bars 25, 26 and 26a is duplicated at each side of the machine and that the breaker plate and the plate 27 above it at their ends are received and guided by said angle guide bar members.
- 55 The sand which is to be treated and renovated is entered into the housing through an entrance stack 28 located at the rear portion of the housing, the cover member 7 and its wearing plate 16 underneath having openings in conjunction with 60 the passage through the chute 28. In practice the sand which has been shaken out of the flasks after a molding operation is carried by a conveyor of the endless belt type which delivers the sand to the upper end of the chute 28. The pulley 65 adjacent the upper end of the entrance chute 28 around which the conveyor passes is of magnetic character so that heavier pieces of iron which may be in the sand are carried around the pulley and do not drop into the upper end of the chute 70 but drop from the conveyor belt after its lower run has been carried away from the magnetic pulley. However smaller pieces of iron, fins, wood pieces and the like, will not be drawn through the sand or be held with sufficient force and they, 75 together with the sand, will drop into the upper

end of the entrance chute 28 and go to the interior of the machine.

A short distance in front of the sand conducting chute 28 is a chimney 29 having a damper 30 therein, the lower end of the chimney communicating with the interior of the machine through openings made in the plates 7 and 16. A fan housing 31 is disposed above and connected to the upper end of the chimney 29 from which an outlet 32 leads to any desired place in the foundry where the machine is used, the fan acting to draw dust, ashes and other sufficiently light materials upwardly and project them out through the outlet at 32, the degree of suction being controlled by the position of the damper 30. 15

The hinged cover member 8 has over it a dome shaped housing 33, the entire bottom of which is open at 34 to the interior of the machine. A vertical partition 35 extends lengthwise of the housing 33 and has its upper edge spaced from 20 the top of the dome. Forwardly of the partition 35 is located a grating or screen 36 inclined longitudinally of the housing and having its lower end communicating with a disposal pipe 36a. This dome and screen act to eliminate chunks 25 of material from the sand as hereafter explained.

Between their front and rear edges and at the lower portions thereof the sides 4 and the wear plates at the inner sides thereof are cut away to provide openings 37. A shaft 38 passes through 30 the machine, at its end portions extending beyond said openings, and is mounted for rotation in bearings 39 carried on horizontal shelves 40 at the outer sides of the machine, and which are supported and reinforced by braces 41 (Fig. 2). 35 Within the machine and between its sides the shaft is equipped with a plurality of preferably equally spaced disks 42. A plurality of rods 43, shown as four in number, extend through said disks a short distance within their peripheral 4 edges, the rods being disposed 90° apart. On said rods between the disks, steel knives 44 are swingingly connected, the rods passing through said knives near one end thereof. These knives 44 on any one of the rods 43 are mounted between alternate disks, as shown in Fig. 2. The outer ends of the knives when they are extended radially outward from the center of the shaft 38, follow a path slightly within the edges of the screen or grating bars 20 (Fig. 1). 50

In the operation of the machine the shaft 39 is rotated at high speed, approximately 1000 R. P. M., in any suitable manner. It can be directly connected with an electric motor or through gearing interposed between the motor 55 and the shaft, or as shown in Fig. 2, it may be driven by a belt passing around a pulley 45 at one end of the shaft. When thus rotating, the knives through centrifugal force are extended radially outward as in Fig. 1. 60

The sand, dropping by gravity through the entrance chute 28, is struck forcibly by said knives and any chunks or masses of sand which adhere together are in effect exploded apart, at least the lumps, chunks or balls of sand are disintegrated and the sand grains substantially separated from each other and from any wood parts, fins or other metal parts while the burned sand, ashes and dust are also fully separated. 65

The suction fan at 31 draws air from the interior of the machine upwardly through the chimney at 29, which air is supplied to the interior of the machine through the openings at 37. This introduction of an air current is considerably aided by the rotating movement of the shaft 38. 70 75

the disks 42 and the knives 44 which have the action of a centrifugal fan or blower tending to draw air into the machine through openings 37 and distribute it radially. The light dust, ashes 5 and the like are carried by the upward current of air and in this manner separated from the sand. The sand in its separated granular form will pass through the narrow slots between the bars 20. Any materials within the sand such as 10 iron fins or other pieces of iron or wood of any character, will not pass between the bars 20 but will be carried by the knives 44 around the bar grating or screen and will leave said knives and be thrown upwardly through the rear of the opening 15 34 into the domed housing 33 and striking the curved top thereof will be carried over unto the screen 36. Some of the sand particles will also be carried over unto this screen 36 and will sift through the screen and drop back through the 20 open lower part of the housing 33 into the interior of the machine. The screen 36 may be sufficiently inclined so that particles dropping thereon will slide by gravity to its lower end and be disposed of through the pipe 36a.

25 The mechanism described and the process which is performed thereby is very practical and useful for the renovation of molding sand which has been used and is to be reconditioned or renovated for subsequent use. The breaker plate 24 is 30 of a heavy structure in cross section for the reason that it is particularly subject to the wearing or abrasive action of the sand, as such sand is initially thrown against it with heavy force, the breaking up of the lumps being accomplished 35 by the knives striking the sand and by the sand striking against the breaker plate 24. Such breaker plate as well as substantially all other parts of the machine which are thus subject to heavy wear are very readily replaceable in the machine 40 which is of a structure such that its disassembly is readily accomplished. In such disassembly of the housing of the machine, particularly the upper part thereof which receives a very great portion of the wear, the shaft 38 and the parts 45 carried thereby are not disturbed. The upper part of the housing can be entirely removed by lifting it upwardly and can be replaced by lowering it from above with the shaft 38 and the disks and knives carried thereby remaining assembled 50 in place.

With the construction of machine as described, the objects and purposes of the invention above recited are completely and fully attained. The machine of course may be used for other purposes 55 than renovating used molding sand, for example, in the pulverizing of limestone in preparing it for the manufacture of cement. The rotation of the shaft 38 has been stated as in the neighborhood of 1000 R. P. M. but of course such rotation 60 may be changed in accordance with differing conditions of operation.

Having thus fully described my invention, what I claim and desire to secure by Letters Patent is as follows.

65 I claim:

1. A machine for renovating molding sand having therein ashes, dust and portions held together in lumps comprising, a main housing to receive said sand, a grating in the bottom of said housing 70 to pass the renovated sand, a plurality of rapidly rotating knives in said housing to contact the

sand as it enters the housing, an outlet chimney at the upper part of the housing having a suction fan therein, a second housing adjacent said chimney above and to one side of said knives and an inclined screen occupying a portion only of said second housing having its lower end leading to a point outside the housings, whereby the dust and ashes stirred up by said knives will be drawn out through the chimney and the lumps will be thrown upwardly on top of said screen to carry 10 out solid refuse and permit the sand particles to be returned to the main housing.

2. A machine for renovating molding sand having therein ashes, dust and portions held together in lumps comprising, a main housing to receive 15 said sand, a plurality of rapidly rotating knives in said housing to contact the sand entering therein, an outlet chimney having a suction fan therein, a second housing in the upper part of said main housing above and to one side of said knives, and an inclined screen in said second housing terminating outside thereof and occupying only a portion thereof to provide a passage between the screen and a side of the second housing, whereby the dust and ashes stirred up by said knives will 25 be drawn out through the chimney and the lumps will be thrown upwardly through said passage onto said screen which will carry out the solid refuse and permit the sand particles to return to 30 the main housing.

3. A machine for renovating molding sand having therein ashes, dust and portions held together in lumps comprising, a main housing to receive said sand, rapidly rotating means in said housing to contact the sand entering therein and stir up 35 the dust and ashes and throw upwardly the lumps therein, a second housing in the upper part of said main housing above and to one side of said rotating means, a screen in said second housing, a passage in said second housing to receive the upwardly thrown lumps and direct them to said screen, whereby the solid particles of the lumps will be carried away and the remaining sand particles permitted to return to the main housing, and means for withdrawing from said main housing the dust and ashes stirred up by said rotating 40 means.

4. In a machine of the class described, a housing into which used molding sand is adapted to be delivered, the lower side of said housing being 50 open, a pair of curved guide bars spaced from each other located at the inner side of each side of the housing, spaced apart removable grate bars carried at their ends between said guide bars, pivotally mounted reversible spacers on some of 55 said bars, means for holding the grate bars against movement, a horizontal shaft, swinging knife members connected with and movable with said shaft, said knife members at their outer ends lying slightly within the inner edges of said grate bars, suction means for withdrawing ashes, dust and light materials from the upper portion of the housing, a domed housing located above the upper side of the front portion of the sand receiving housing, there being an opening from said sand receiving housing to said domed housing at the lower front portion of the latter, and conveyor means mounted in said domed housing for disposal of heavy materials thrown upwardly by said knife members into the domed housing.

70 WILLARD J. BELL.
